WASH FOUNTAIN

Joseph Rothmayr, Zurich, Switzerland, assignor
to Interpatenta-Trust, Vaduz, Principality of
Liechtenstein

Application May 18, 1950, Serial No. 162,651
In Switzerland February 22, 1950

5 Claims. (Cl. 299—140)

1

My present invention relates generally to wash fountains such as are used in shops, mills and factories for the convenience of the workers and, in particular, to valve means incorporated therein for controlling the flow of water therefrom with a view of saving water.

In wash fountains known in the art, there is provided a wash-water distributing chamber comprising at least one circumferential row of apertures for the outflowing water. The wash water in such known fountains flows simultaneously from all the spouts or nozzles. When only a few persons wash themselves, all the spouts or nozzles are in operation, which arrangement thus leads to an excessive water consumption and is particularly objectionable when using hot water.

In order to avoid the said disadvantage, I provide in said distributing chamber an axially movable regulator element which is adapted to uncover the spouts in succession as desired.

Two forms of my present invention, including three modifications of a valve component member, are shown in the accompanying drawing in which—

Fig. 1 is a view of a wash fountain according to a first form, the pedestal and basin being shown in section.

Fig. 2 shows an enlarged axial section of part of Fig. 1.

Fig. 3 is an axial section of part of a second form, and

Figs. 4—6 show each a modified form of the regulator element.

A water supply pipe 2 (Fig. 2), e. g. for supplying cold water to the fountain, is disposed coaxially in a column 1 which is surrounded by a circular wash basin and serves for supplying hot water for example. A cap 3 provided with a transverse wall 4 closes the top of column 1, a nut 5 and a ring gasket 6 being provided for a seal. Two valve seats 8 are screwed into the wall 4, and a port 7 integral with cap 3 connects the pipe 2 with one of the valves. A distributing chamber 9 is secured to the cap 3 on top thereof. A rising valve stem 10 is threadedly engaged at 11 to said chamber 9 and sealed by means of a stuffing box comprising a packing means 12 and a gland 13. The stem 10 at its upper end is provided with a knob 14 and, at its lower end, with a disc 15 which is engaged by a screw cap 16 so as to rotatably connect the stem 10 to a regulating element in form of a piston valve 17. The latter is inserted in the distributing chamber 9 in fluid-tight relation and is axially movable therein by means of the stem 10. Two valve discs 18 are fixed to the underside of the slide 17

2

to coact with the valve seats 8. Two rows of discharge openings 19 are provided on the circumference of the chamber 9. The said openings are situated above the top surface of the piston 17 when the valves are closed, as shown in Fig. 2.

The lower or control edge 23 of the piston valve 17 is so designed that the latter on moving upwardly uncovers the openings only successively for water discharge. Only when the edge 23 is in its topmost position, all the openings 19 are uncovered. The piston-valve edge 23 may extend askew of the axis of the piston valve 17 (Fig. 4), or at right angles thereto and stepped back a plurality of times (Fig. 5), or it may extend partly askew to the said axis and partly be stepped back (Fig. 6). The discharge openings 19 are uncovered step by step, and the magnitude of the steps may be different. With the form shown in Fig. 4, the openings 19 are uncovered in succession, while with the forms shown in Figs. 5 and 6 the openings are uncovered step by step, for example $\frac{1}{8}$, $\frac{1}{4}$, $\frac{1}{3}$, $\frac{1}{2}$, $\frac{3}{4}$ and then all thereof.

25 A displacement element 20 is fixed to the underside of each valve disc 18 and is of such shape as to regulate the rate of water inflow into the chamber 19 with a view of obtaining jets of substantially equal spouting reach, irrespective of whether all of the jets or only part of them issue.

In order to positively locate the reduced water discharge, it is necessary to prevent the piston valve 17 from rotating in the distributing chamber 9. Means (not shown) are provided for such purpose.

The form of wash fountain shown in Fig. 3 comprises only one water supply pipe, i. e. the column 1 serves as supply conduit, e. g. for cold water. There is only one valve seat 8 in the transverse wall 4, which seat is co-axial with the stem 10 and co-acts with a valve disc 18 which is integral with the stem 10. For regulating the size of the discharge openings 19, a ring 25 provided with apertures 24 is rotatably mounted on the outside of the distributing chamber 9.

In order to prevent the piston valve 17 from rotating, a vertical stud 21 is fixed to the distributing chamber and passes through a vertical bore in the piston valve 17.

One, two or more circumferential rows of openings 19 may be provided for. The said openings may be in form of grooves in a ring which is inserted at a corresponding elevation in a two-part distributing chamber between the two parts thereof. The said ring may be readily replaced.

The said grooves may be provided on one or on both ring end-faces and may be of unequal cross-sections.

What I claim as new and desire to secure by Letters Patent is:

1. A wash fountain comprising a distributing chamber, an inlet to said chamber, a plurality of circumferentially arranged outlets from said chamber, regulating means for uncovering said outlets in said chamber in succession, operating means for moving said regulating means axially in said chamber over said outlets, means for preventing rotatable movement of said regulating means, and a second regulating means for controlling the size of said outlets. 10

2. A wash fountain as in claim 1, in which said first regulating means comprises a piston having a circumferential control edge of substantially helical shape.

3. A wash fountain as in claim 1, in which said second regulating means includes a perforated ring rotatably mounted on the outside of said chamber for control of the size of said outlet openings. 20

4. A wash fountain as in claim 1, including 25 regulating means for said inlet, and means con-

necting said inlet regulating means to said outlet regulating means whereby the flow-rate through said inlet is controlled in dependence upon the flow rate through said outlets.

5. A wash fountain as in claim 4, including a second inlet to said distributing chamber, and regulating means for said second inlet operatively connected with said regulating means for said first mentioned inlet.

JOSEPH ROTHMAYR.
